UNITED STATES PATENT OFFICE.

LUCIAN M. SIMMONS, OF REYNOLDSVILLE, PENNSYLVANIA.

GAS-MIXER.

No. 904,368.

Specification of Letters Patent.

Patented Nov. 17, 1908.

Application filed March 27, 1908. Serial No. 423,548.

To all whom it may concern:

Be it known that I, LUCIAN M. SIMMONS, a citizen of the United States, and a resident of Reynoldsville, in the county of Jefferson and State of Pennsylvania, have invented a new and Improved Gas-Mixer, of which the following is a full, clear, and exact description.

This invention relates to certain improvements in devices adapted for use in mixing air and gas and delivering the mixture to a burner.

More particularly, the invention relates to that type of mixer in which there is employed a tube adapted to be connected to a source of gas at one end and adapted to be connected to a burner at the opposite end, and having within the tube a helical baffle to bring out the thorough and complete commingling of the gas and air, and to produce a uniform mixture thereof, so that there will be perfect combustion of the gas.

The special object of the invention is to provide a single article in which the tube and baffle are formed integral, and in which the gas and air enter through concentric passages to the end of said baffle and are caused to move in a helical path toward the connections with the burner.

Reference is to be had to the accompanying drawings, forming a part of this specification, in which similar characters of reference indicate corresponding parts in both the figures, and in which

Figure 1 is a longitudinal section through a mechanism constructed in accordance with my invention, the baffle being shown in side elevation, said section being taken on the line 1—1 of Fig. 2; and Fig. 2 is a transverse section on the line 2—2 of Fig. 1.

In the specific form of my improved mixer illustrated in the accompanying drawings, I provide a tube or body 10, having one end thereof reduced to form a neck 11, which may be interiorly threaded to adapt it for connection to a burner. The opposite end of the tube is open and concentric with the open end is a nozzle 12, threaded for attachment to a suitable conduit for supplying the gas. The nozzle is preferably formed integral with the body of the tube and is connected thereto by a plurality of radial arms

13. The inner end of the nozzle is preferably within the outer end of the tube, and the arms connect with the outer end of the nozzle adjacent the point at which the conduit or supply pipe is attached.

Within the body and, preferably integral therewith, I provide a central core 14, concentric with the body and connected thereto by two oppositely-disposed helical partitions or baffles 15. The two baffles terminate in alinement with each other adjacent the reduced portion, connecting the body to the threaded neck 11, and at the opposite end terminate in a screw point 16, concentric with the nozzle 12. The gas in entering the nozzle 12, strikes the screw point 16, so that the gas is divided into two streams, each of which unites with air entering through the opening surrounding the nozzle 12. In traveling upward through the two helical passageways, the gas and air are thoroughly intermixed and commingled, so as to produce a perfect and complete combustion at the burner.

All of the parts of the mixer are formed integral, so that it is impossible for a portion thereof to become detached or disarranged, or to require adjustment. The device is very simple in construction and may be readily applied to any suitable burner. The reduction in size of the neck 11 accommodates for the space taken by the baffle and core, so that there is substantially a uniform flow through the mixer.

Having thus described my invention, I claim as new and desire to secure by Letters Patent:

1. A gas mixer, comprising a tubular body having one end thereof adapted to be attached to a burner and having the opposite end thereof open, a gas delivery nozzle concentric with said body, means connecting said nozzle and said body at the open end thereof, and a helical baffle within said body and terminating in a screw point concentric with said nozzle.

2. A gas mixer, comprising a tubular body having one end thereof of reduced diameter and adapted to be attached to a burner and having the opposite end thereof open, a gas delivery nozzle concentric with said body at the open end thereof and connected to said

body by a plurality of radially-disposed arms integral with the body and with the nozzle, and a baffle within said body, including a central core and baffle plates connecting said core and the body and integral with both, said baffle terminating in a screw point concentric with said nozzle and adjacent thereto.

In testimony whereof I have signed my name to this specification in the presence of 10 two subscribing witnesses.

LUCIAN M. SIMMONS.
